Fig. 2

Fig. 3

Fig. 4

Fig. 5

Fig. 6

FIG. 1 is a front elevation of an infant chair showing our new design;

FIG. 2 is a side elevation thereof;

FIG. 3 is a rear elevation thereof;

FIG. 4 is a plan view thereof;

FIG. 5 is another side elevation similar to FIG. 2 but showing the chair in another position of adjustment; and

FIG. 6 is another side elevation similar to FIG. 2 but showing the chair in still another position of adjustment. We claim:

The ornamental design for an infant chair, as shown and described.
